[57] CLAIM

The ornamental design for a holder for a credit or transaction card, as shown and described.

DESCRIPTION

FIG. 1 is a front perspective view of my holder for a credit or transaction card;

FIG. 2 is a top plan view thereof;

FIG. 3 is a front elevational view thereof;

a mirror image thereof;

FIG. 5 is a bottom plan view thereof; and,

FIG. 6 is a rear elevational view thereof.
